[57] CLAIM

The ornamental design for a panty hose sizing form, substantially as shown and described.

DESCRIPTION

FIG. 1 is a front isometric view of a panty hose sizing form showing our new design;

FIG. 2 is a front elevational view, the rear being identical;

FIG. 3 is a right side elevational view thereof;

FIG. 4 is a top plan view thereof.

FIG-1FIG-2FIG-4FIG-3
